UNITED STATES PATENT OFFICE.

MARTIN ARNOLD JAQUES, OF LONDON, ENGLAND.

DESIGN FOR A HAND-STAMP.

SPECIFICATION forming part of Design No. 31,743, dated October 31, 1899.

Application filed October 6, 1899. Serial No. 732,824. Term of patent 14 years.

To all whom it may concern:

Be it known that I, MARTIN ARNOLD JAQUES, a subject of the Queen of England, residing at Ealing, London, England, have invented and produced a new and original Design for Hand-Stamps, of which the following is a specification, reference being had to the accompanying drawings, forming part thereof.

In the accompanying drawings, Figure 1 is a side elevation, and Fig. 2 is a plan of the same, embodying my design.

The leading feature of the design resides in the configuration and in the relative position of the base-plate and the handle. The

base-plate is shown at B and C, while the handle A extends upwardly at an angle therefrom.

What I claim is—

The design for a hand-stamp as herein shown and described.

In testimony whereof I have signed my name to this specification in the presence of two subscribing witnesses.

MARTIN ARNOLD JAQUES.

Witnesses:

JOSEPH LAKE,
W. M. HARRIS.
